UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

LOOPER-ROCKER FOR SEWING-MACHINES.

1,135,405.

Specification of Letters Patent. Patented Apr. 13, 1915.

Original application filed August 8, 1908, Serial No. 447,536. Divided and this application filed November 26, 1909. Serial No. 530,015.

To all whom it may concern:

Be it known that I, DUDLEY S. SEYMOUR, a citizen of the United States, residing at Oak Park, in the county of Cook, State of Illinois, have invented certain new and useful Improvements in Looper-Rockers for Sewing-Machines, of which the following is a description, reference being had to the accompanying drawing and to the letters 10 and figures of reference marked thereon.

The invention relates to new and useful improvements in looper rockers for sewing machines, and has for an object to provide a looper rocker which is capable of supporting a looper and imparting thereto the lateral or needle avoiding movements, and which is also capable of imparting to some independent element of the sewing machine, an oscillating movement.

20 This application is a division of my co-pending application, Serial No. 447,536, filed August 8th, 1908.

In the drawings which show by way of illustration one embodiment of the invention, Figure 1 is a side view with the parts removed showing a machine with my looper rocker mounted therein. Fig. 2 is a transverse sectional view of the looper rocker showing the operating means therefor, and 30 said looper rocker connected to the feed bar of the machine. Fig. 3 is a perspective view of the looper rocker detached.

My looper rocker is preferably used in a sewing machine which is provided with an 35 overhanging arm 1, which carries a needle bar supporting a needle 2. The needle bar is reciprocated by the usual needle lever 3. Said sewing machine is also preferably provided with a feed dog 4, carried by the usual 40 feed bar at its forward end, and said feed bar is pivoted at its rear end to a feed rocker 5. The feed bar as herein shown is also provided with a downwardly projecting arm 6, which is carried forward under- 45 beneath the main shaft 7. The looper rocker 8 as clearly shown in Fig. 3 is formed with a body portion which is yoke shaped. Said body portion intermediate its ends carries a bearing or supporting stud 9 for the looper. 50 The looper 10 is pivotally supported by said stud, and is vibrated into and out of the needle loop by a link connection 11 with the needle lever 3. The looper rocker at one end

carries a projecting stud 12 which is mounted in a bracket 13 at the forward end of the 55 machine. Said looper rocker is attached to a short shaft 14 at its other end which projects through a bearing carried by a bracket 15.

An arm 16 is mounted on the end of the 60 short shaft 14, and in turn is connected to an eccentric strap 17 co-operating with an eccentric on the main shaft. The arm 16 also has a connection to the feed rocker for moving the feed bar back and forth. 65 As the main shaft rotates the looper rocker will be vibrated laterally through the eccentric and its connecting arm 16. The looper rocker is also provided with a laterally projecting arm 18. Said arm is 70 mounted on the looper rocker on the offset part of the body portion, so that said arm will swing bodily with the looper rocker, as it is oscillated laterally. The arm 18 is connected by means of a link 19 as herein 75 shown, to the downwardly projecting arm supported by the feed bar. I have also shown a second arm 20 which is similar to the arm 18 and which is connected by a second link with the feed bar. It is obvious 80 however, that instead of using the two arms, one arm may be employed. The sole purpose of the second arm is to give greater strength to the operating parts.

In the operation of my device, the needle 85 is reciprocated into and out of the material and the looper moved into and out of the needle loop by means of the usual needle lever. The looper rocker is oscillated about its axis in order to give the looper a needle 90 avoiding movement by means of the connection with the eccentric on the main shaft, which moves the feed bar back and forth. As the looper rocker oscillates about its axis, the laterally projecting arm carried by 95 the body portion, also will be oscillated and through its link connection with the feed bar, impart the up and down movements to the feed bar.

Having thus particularly described my 100 invention, what I claim as new and desire to secure by Letters Patent, is:

1. A looper rocker comprising an offset body portion for supporting the looper, means whereby the looper rocker may be 105 supported, and a laterally projecting arm

carried by the offset body portion, which arm is adapted to impart the lateral movements of the looper rocker to a moving part of the machine.

5. 2. A looper rocker comprising a yoke-shaped body portion, means whereby the looper rocker may be supported, means whereby a looper may be supported on said rocker, and a laterally projecting arm carried by the body portion which arm is adapted to impart the lateral movements of the looper rocker to a moving part of the machine.

15. 3. A looper rocker comprising a yoke-shaped body portion, means whereby said looper rocker may be supported, a bearing intermediate the ends of the rocker on which a looper may be pivoted, a laterally projecting arm carried by the body portion of 20 the rocker and adapted to impart the lateral movements of the rocker to a moving part of the machine.

4. A looper rocker comprising a yoke-shaped body portion, means whereby said looper rocker may be supported, a bearing intermediate the ends of the looper rocker 25 on which the looper may be pivoted, said looper rocker having an integrally formed arm projecting laterally therefrom, said arm being located in a plane substantially at right angles to the looper rocker and the longitudinal axis of said arm being eccentric

to the axis of said looper rocker, whereby as said looper rocker is oscillated, said arm will move bodily about the axis of the looper 35 rocker, said arm having means for connection with a moving part of the machine.

5. A looper support adapted to oscillate about an axis, a member carried by said support and oscillating therewith, said member being disposed in a plane substantially at right angles to the axis of the looper support and eccentrically located relative thereto, and adapted to be connected to a movable part of the machine.

45. 6. A looper mechanism comprising a looper, a looper support on which said looper is pivoted, means for giving the looper a movement on its pivot into and out of the needle loop, means for moving the looper support, whereby said looper is given a needle-avoiding movement, and devices carried by the looper support and extending in a direction substantially at right angles to the longitudinal axis of the looper 50 support for supporting one end of a moving part of the machine and imparting movement thereto.

55. In testimony whereof I affix my signature, in presence of two witnesses.

DUDLEY S. SEYMOUR.
